DESIGN FOR A PAINT STIRRER

Paul Marienthal, Detroit, Mich.

Application November 25, 1940, Serial No. 96,800

Term of patent 14 years

To all whom it may concern:

Be it known that I, Paul Marienthal, a citizen of the United States of America, residing at Detroit, in the county of Wayne, in the State of Michigan, have invented a new, original, and ornamental Design for a Paint Stirrer, of which the following is a specification, reference being had therein to the accompanying drawing, forming a part thereof, wherein:

I claim:

The ornamental design for a paint stirrer, substantially as shown,

PAUL MARIENTHAL.
